UNITED STATES PATENT OFFICE.

WILLIAM C. HARTMANN AND EDWARD A. WEISS, OF CLEVELAND, OHIO.

AUXILIARY BED RAIL AND SLAT SUPPORT.

Application filed December 13, 1926. Serial No. 154,529.

The invention aims to provide a new and improved device which will serve as an auxiliary support for side rails of a bed and will also act to effectively support the ends 5 of slats extending between said rails, so that there is no danger of the slats dropping and causing possible injury to the occupants of the bed.

With the foregoing in view, the invention 10 resides in the novel subject matter herein-after described and claimed, the description being supplemented by the accompanying drawing.

Fig. 1 is a fragmentary side elevation 15 showing the application of the invention.

Fig. 2 is a top plan view.

Fig. 3 is a vertical sectional view on line 3—3 of Fig. 1.

Fig. 4 is a vertical section on line 4—4 20 of Fig. 3.

In the drawing above briefly described, R designates the side rails of a bed, connecting the head and foot H and F thereof, in the usual way. The supports S, constituting the present invention, may be connected with the rails R at any desired points, and when so connected they serve as auxiliary supports for said rails, as well as supports for slats S'.

Each support embodies a leg 5 which is 30 preferably of tubular form to receive the shank of a caster 6, this caster being preferably vertically adjustable by means of a nut 7. The details of the caster construction and mounting constitute no part of the present invention.

The upper end of the leg 5 is provided 40 with two seats, one for the rail R and the other for the slat S'. In the present showing, a vertical plate 8 is rigidly joined in any desired manner to the upper end of the leg and is provided with lateral flanges 9 and 10 which project in opposite directions. The flange 9 is intended to underlie the rail 45 R and is preferably provided with a ridge 11 along its outer edge to engage the outer side of said rail. The flange 10 acts as a support for the slat S' and is provided with upstanding lugs 12 to straddle said slat and 50 hold the latter against lateral slippage from the flange. Preferably, the parts 8, 9, 10, 11 and 12 are cast as a single piece, which piece may be rigidly joined to the leg 5 in any desired manner.

The invention is simple and inexpensive, yet will be efficient and reliable for the pur-

poses intended. On account of the excellent results obtainable from the details disclosed, such details are preferably followed. However, within the scope of the invention as 60 claimed, variations may be made.

We claim:

1. An auxiliary bed rail and slat support comprising a leg having a seat at its upper end for attachment to the rail, and a second 65 seat rigid with the first named seat for supporting one end of a slat said second seat embodying means to abut the longitudinal edges of the slat to hold it against slippage from the seat.

2. An auxiliary bed rail and slat support comprising a leg having a vertically disposed rigidly attached plate at its upper end for attachment to the inner side of the rail, said plate being formed with a laterally 75 projecting flange to support one end of a slat, said flange having upstanding lugs to straddle the slat and hold the same against lateral slippage.

3. An auxiliary bed rail and slat support 80 comprising a leg having a vertically disposed rigidly attached plate at its upper end for attachment to the inner side of the rail, said plate being formed with two flanges projecting laterally in opposite directions, 85 one of said flanges being adapted to contact with the lower edge of the rail and the other flange constituting a slat support, said other flange having upstanding lugs to straddle the slat and hold it against lateral slippage. 90

4. An auxiliary bed rail and slat support 95 comprising a leg having a vertically disposed plate at its upper end for attachment to the rail, a slat supporting flange formed on and projecting from the side of said plate opposite to the side which engages the rail and means for holding the slat in engagement with said flange.

5. In a bed structure having two parallel 100 side rails, auxiliary supporting legs for said rails, means securing the upper ends of said auxiliary legs to said rails, a transverse slat extending between the upper ends of said legs, and inwardly projecting seats on said upper ends of the legs, said seats being engaged with the ends of said slat to support the latter in operative position.

In testimony whereof we have hereunto affixed our signatures.

WILLIAM C. HARTMANN.
EDWARD A. WEISS.
